UNITED STATES PATENT OFFICE.

MAX C. BATSEL, OF WILKINSBURG, PENNSYLVANIA, ASSIGNOR TO WESTINGHOUSE ELECTRIC & MANUFACTURING COMPANY, A CORPORATION OF PENNSYLVANIA.

WIRELESS RECEIVING APPARATUS.

Application filed October 4, 1922. Serial No. 592,234.

To all whom it may concern:

Be it known that I, MAX C. BATSEL, a citizen of the United States, and a resident of Wilkinsburg, in the county of Allegheny and State of Pennsylvania, have invented a new and useful Improvement in Wireless Receiving Apparatus, of which the following is a specification.

My invention relates to wireless receiving apparatus and more especially to mountings for vacuum tubes employed in such apparatus.

In its broad aspect, an object of my invention is to provide a mounting for vacuum tubes which effectually protects the tubes from local shocks or disturbances.

More specifically, another object of my invention is to provide means which limit the motion of the vacuum-tube base socket when force is exerted thereon, as obtains during the insertion of a vacuum tube therein, said limiting means also serving as a terminal support for the flexible leads extending from the base socket.

A further object of my invention is to provide apparatus of the class described which is of simple, compact, and rugged design and which is susceptible of inexpensive quantity-production methods of manufacture, the several parts thereof being readily manufactured in existing automatic machinery and being readily assembled with a minimum expenditure of time and money.

It is well known that, when a vacuum tube is subjected to a sudden shock, the several elements contained within the tube are set to vibrating according to the natural periods thereof. The vibration of the elements causes variations in the relative spacing thereof and, consequently, alters the characteristics of the tube, thereby resulting in noisy and inefficient operation.

According to my invention, I provide a shock-absorbing cradle for the tubes, whereby the effects of local vibration are eliminated, and whereby a terminal support is provided for the flexible conductors leading from the base socket. The structure for accomplishing the above mentioned results comprises a base-socket panel having opposite ends resiliently secured to fixed supports. In a preferred form of embodiment of my invention, the fixed supports are provided by a main operating panel, which also controls the operation of the tubes, and

a sub-panel, which also provides a support for terminal connectors. The sub-panel may be rigidly secured to the main operating panel in a manner hereinafter set forth, and the whole structure is removably positioned in a cabinet with the control panel constituting a closure therefor.

With these and other objects and other applications in view, my invention further consists in the details of construction and arrangement hereinafter described and claimed and illustrated in the accompanying drawing, wherein

Figure 1 is a vertical longitudinal sectional view of a wireless receiving cabinet embodying my invention, the section being taken on the line I—I of Fig. 2, and

Fig. 2 is a horizontal sectional view of the structure shown in Fig. 1, the section plane being indicated by the line II—II of Fig. 1.

In the illustrated form of embodiment of my invention shown in the drawing, a cabinet 1 is provided which is open in front and which is provided with perforations 2 in a rear wall 3 thereof, the perforations 2 removably receiving external circuit terminals 4 for the apparatus contained within the cabinet 1. Access to the interior of the cabinet 1 through the outside thereof is provided through an opening 5 in the top.

A main panel 6, which constitutes a closure for the front end of the cabinet 1 and which also serves as a control panel, has rigidly secured, in spaced relation to its inner surface, a sub-panel 7, the two panels being connected by means of supporting rods 8. The length of the supporting rods 8 is such as to position the sub-panel 7 immediately adjacent to the rear wall 3 of the cabinet 1. The plurality of terminal connectors 4 are carried by the sub-panel 7 and extend through the perforations 2 in the rear wall 3, thereby providing connections accessible from the outside of the cabinet 1.

A vacuum-tube base-socket panel 9, carrying a plurality of socket devices 11, having flexible terminal leads 12, is horizontally positioned in its place between the two panels 6 and 7 in such manner as to provide a support for tubes (not shown) which are normally inserted through the opening 5, in the top side of the cabinet 1. The panel 9 may be resiliently supported by means of a pair of rubber straps 13 and 14 which are secured to opposite edges thereof by means

of clamping members 15 and which are provided with extensions 16 and 17, respectively, secured to supporting blocks 18, carried on the inner sides of the panels 6 and 7.

5 The ends of extension 16 and 17 may be secured to supporting blocks 18 by means of clamping members 19.

The extensions 16 and 17 have just sufficient strength to support panel 9, and apparatus carried thereby, hence providing an extremely flexible connection. Such construction, however, has a disadvantage that when a force is brought to bear upon the vacuum-tube socket panel 9, as by the insertion

10 of a tube in one of the socket devices 11, the material of the resilient extensions 16 and 17 may be stretched beyond its elastic limit, thereby destroying the resiliency of the mounting.

15 20 The foregoing undesired result is overcome, in my invention, by the provision of stationary bars 21 and 22 which are so disposed as to limit the displacement of the base socket panel 9 to a safe amount. The bars 21 and 22 are disposed directly beneath the outer edges of the base socket panel 9 and have their opposite ends secured to the blocks 18 by means of screw connectors 23. The bars are also provided with a number

25 30 of stationary electrical connectors 24 to which the flexible leads 12 of the socket device may be secured. Hence the bars 21 and 22 also serve as terminal supports.

35 A pair of filament rheostats 25 and 26 are secured to the inside surface of the control panel 6 directly beneath the base-socket panel 9 and may be operated by knobs 27 and 28, respectively, which are mounted on the outer surface of the control panel 6.

40 45 One or more telephone jacks 29 of well known design are mounted in the control panel 6 directly beneath the rheostats 25 and 26. In order that the description of my invention may be simplified, I have omitted the circuit connections contained in the apparatus and also such additional apparatus as was not essential to a clear understanding of my invention.

50 55 In summary, it will be seen that I provide a resilient mounting for fragile vacuum-tube structures, whereby protection is afforded against external shocks or disturbances. In addition, means are provided which not only limit the displacement of the resilient mounting panel 9, carrying the tubes (not shown) to a predetermined amount but also provides a fixed support for the flexible leads 12 of the socket devices 11.

While I have described a certain form of embodiment of my invention in detail and while I have pointed out certain of the most obvious principles and purposes thereof, I do not intend that the language employed in the following claims shall be limited to the precise features described, but I intend that claims shall be construed to cover all combinations which are fairly included in the language thereof when read in connection with the prior art, regardless of the details and functions mentioned in the description or illustrated in the drawing.

60 65 I claim as my invention:

1. In combination, a pair of vertically positioned panels, means for rigidly securing said panels in such spaced relation as to provide an open space therebetween, a base-socket member horizontally positioned in said open space and having opposite ends resiliently secured to adjacent panels, a pair of members having opposite ends rigidly secured to said panels and horizontally positioned immediately adjacent to the under surface of said base-socket member to limit the motion thereof to a predetermined amount, and electrical connectors mounted on said members.

70 75 80 85 90 95 100 105 110 115 2. In combination, a pair of vertically positioned panels, means for rigidly securing said panels in such spaced relation as to provide an open space therebetween, a base-socket member horizontally positioned in said open space and having opposite ends resiliently secured to adjacent panels, contact-socket devices having flexible terminal leads carried by said base member, a pair of members having opposite ends rigidly secured to said panels and horizontally positioned immediately adjacent to the under surface of said base-socket member to limit the displacement of the base member, and electrical terminal connectors mounted on one or both of said pair of members.
